Inventor:
Benjamin F. Allin &
Béné Rain & Hinkle
By Attest.

UNITED STATES PATENT OFFICE.

BENJAMIN F. ALLNUTT, OF CHICAGO, ILLINOIS.

FILLING TUBE FOR LIQUID RECEPTACLES.

Application filed August 10, 1921. Serial No. 491,078.

To all whom it may concern:

Be it known that I, BENJAMIN F. ALLNUTT, a citizen of the United States, residing at Chicago, in the county of Cook and State 5 of Illinois, have invented certain new and useful Improvements in Filling Tubes for Liquid Receptacles, of which the following is a specification.

The invention relates to improvements in 10 filling tubes for liquid receptacles, and it is especially well adapted for use in receptacles in which gasoline, benzine, naphtha and other explosive liquids, volatile at a relatively low degree and of high explosive char- 15 acter are to be contained.

The particular use for which the device is best suited is in connection with gasoline storage tanks of automobiles, and the like, in 20 which air is drawn into the tank to displace the liquid or gas taken therefrom to supply the engine.

One of the objects of the invention is to provide an air strainer to prevent entrance of dust into the reservoir, or tank. An- 25 other object is to provide a liquid strainer having openings therein equal or greater in volume than the axial opening of the tube, so that the permeable side wall will not interpose any material retarding effect or re- 30 sistance to the flow of liquid when the tank is being filled.

Another object is to provide an improved closure for the filling tube.

Another object is to provide a resident 35 closure for the filling opening in the tank, which will automatically close said opening after the filling tube has been removed from the tank.

Another object is to generally improve 40 structures of this character.

Other and more specific objects and ad- 45 vantages will readily appear from a consider- 50 ation of the specification when taken in conjunction with the accompanying draw- 55 ing, forming a part hereof wherein;

Fig. 1 is a longitudinal, axial section of the device.

Fig. 2 is an elevation of the device as it 60 appears in a tank.

Fig. 3 is a transverse section taken be- 65 tween the cap and flange of Fig. 1.

In all the views the same reference char- 70 acters indicate similar parts.

The tube 5 is foraminous in character, 75 such as may be made of a closely perforated sheet of metal or wire cloth and of such mesh

or apertures that all objectionable matter held in suspension will be caught in the tube. The vertical wall of the tube has openings equal or greater in the aggregate volume 60 than its bore, so as not to impede the incoming liquid by restricting its flow. When the tank is nearly full the pressure of the incoming liquid will cause its flow throughout the entire length thereof into the tank, 65 so that the entire length of tube is available at all times to convey the liquid.

An imperforate guard tube 6, relatively short in length, is placed in the upper end of the strainer tube, to protect the latter from 70 injury and to provide an air space 7 between the tubes into which liquid from the filling nozzle can not enter, so that air from the tank may pass freely therefrom as the tank is being filled with liquid. The guard tube 75 6 terminates at its upper end in a screw threaded head 8 which is provided with axial, circumferentially extending openings 9 which communicate with the air space therebelow. The head 8 is threaded as at 80 10, for insertion in an internally threaded flange 11. The tube 5 is soldered or otherwise secured at its upper end to guard tube 6; it may, therefore, be withdrawn from the flange. 85

The flange 11 is to be secured above an opening in a tank 12 in any suitable manner. A closure 13 for the flange 11 is provided with laterally extending arms 14 and 15, hinged to arms 16 and 17, respectively, 90 that extend laterally from one side of the flange 11. A pintle pin 18 passes through all of the aforesaid arms and a spring 19 is wound about the pin to yieldingly hold the closure on the flange 11 to close the opening 95 in the tank whether the tube 5 is therein or not. A heel 20 projects from the hinge member 14 for contact with the flange 11 and operates as a stop to limit the extent to which the closure may be moved on its 100 hinges. The closure 13 consists of the cup- shape member 21 to which the arms 14 and 15 are attached, which is screw threaded, at 22, to receive an imperforate cover 23, which is threaded at 24 to engage the threads 22. 105 The member 21 is perforated through its wall, at 25, for entrance of air into the chamber 26. Near the axis of the member 21, and projecting outwardly therefrom, is a hollow hub, 27, perforated as at 28 for entrance of 110 air into its axial bore 29. There is also a hollow hub 30 threaded internally and ex-

ternally, and containing an inwardly opening check valve 31 adjustable by the spring 32 and the hollow nut 33.

An annular rib 34 is located between the wall 22 and the hub 27 in the chamber 26 to cause the incoming air to move upwardly through the fibrous material, such as loose cotton, or the like, to catch the dust and strain the air that enters the tank through 10 the bore 29 of the closure.

After the cotton, or other loose, fibrous material, has become dust laden it may be taken from the chamber and cleaned and replaced, or new material of like character 15 may be substituted.

Owing to the relatively large capacity of the holes 25 and of the fibrous filtering material, there is very slight resistance interposed to the incoming air.

20 It will be understood, of course, that the tendency towards vacuum in the tank 12, due to the discharge of liquid therefrom unseats the valve 31 which permits the entrance of air into the tank through the air 25 strainer described and, to an extent, satisfies the vacuum tendency, at the same time the dust and other material, in a finely divided state, carried by the incoming air, is strained out and caught by the fibrous material in the chamber 26, water resulting from 30 rain, or snow, can not enter the tank with the air owing to the overhanging flange 35 which extends downwardly from the cover cap 23.

35 When the closure is swung on its hinges to fill the tank the air chamber and surrounding casing is movable with it, and the closure is resident with the tank and is not

removed when the tube 5 is taken out for 40 cleaning.

A packing ring 36, of leather or other suitable material, is seated on the top edge 37 of the flange 11 and is held in place by the nut 38 which has threaded engagement with the hub 30.

Besides serving as a liquid strainer the tube 5 serves as means for preventing explosion of the very volatile liquids to be contained in the tank, on the principle of the safety lamp of Sir Humphrey Davy.

50 While one embodiment of the invention has been herein disclosed it will be manifest that changes may be made in the arrangement and disposition of the parts within the scope of the appended claim.

55 Having described my invention what I claim as new and desire to secure by Letters Patent, is:

A filling structure for a liquid receptacle comprising a flanged internally threaded collar for permanent attachment to a receptacle; a closure cap hinged thereto providing an inwardly extending concentric hollow hub; an inwardly opening check valve within the hub; means within the hub to adjust the valve; a screw cap closing the outer end of the closure cap; a foraminous tube insertible within the tank through said collar and an imperforate guard tube within the foraminous tube attached thereto and 60 having a threaded head for threaded engagement with the threads of the flanged collar.

65 . In testimony whereof I hereunto subscribe my name.

BENJAMIN F. ALLNUTT.
